J. ISOJOKI

SPARK CONTROL FOR INTERNAL COMBUSTION ENGINES

Filed Sept. 20, 1923

UNITED STATES PATENT OFFICE.

JALMER ISOJOKI, OF DETROIT, MICHIGAN.

SPARK CONTROL FOR INTERNAL-COMBUSTION ENGINES.

Application filed September 20, 1923. Serial No. 663,757.

To all whom it may concern:

Be it known that I, JALMER ISOJOKI, a citizen of the United States, residing at Detroit, in the county of Wayne and State of Michigan, have invented certain new and useful Improvements in Spark Controls for Internal-Combustion Engines, of which the following is a specification.

This invention relates to an automatic 10 spark control mechanism for internal combustion engines.

It is aimed to provide an inexpensive, efficient and durable means operable automatically according to the speed of the engine in order to vary the time of production 15 of the spark or firing, that is, advance or retard it.

Another object is to provide a novel means to accomplish the end stated which is 20 controlled by a governor.

Various additional objects and advantages will appear from the description following, taken in connection with the accompanying drawings illustrating an operative embodiment.

In said drawings:—

Figure 1 is a view showing the device in elevation;

Figure 2 is a sectional view taken substantially on the line 2—2 of Figure 1, and

Figure 3 is a side view of the timer.

Like reference characters designate like or corresponding parts in the different views.

The invention is practiced in connection 35 with a timer or commutator such as is used on automobiles, tractors and the like and a conventional form of which is shown at 10 having a shell or casing 11, provided with contacts 12 at spaced intervals and which are adapted to be wiped by a contact roller 13 in order to successively close and open 40 electric circuits through the spark plugs of the cylinders of the engine in a manner well understood. The contacts 12 are insulated 45 from the wheel as at 14 and the roller 13 is carried by a bracket 15 fastened on a shaft 16 rotatably mounted in the shell. The shell is also capable of slight rotary or turning movement about the axis of shaft 16 and in- 50 dependently thereof.

A governor rod or shaft 17 is journalled and fastened against longitudinal movement in a suitable bracket 18, fastened to any suitable support or part on the automobile or tractor. Shaft 17 has a bevel gear 19 fixed thereon which meshes with a bevel gear 20, keyed on shaft 16. 55

Slidably disposed on shaft 17 is a sleeve 21, which is in turn slidable through a hollow arm 22 of a bracket 23 adapted for 60 connection to a suitable part of the automobile or tractor. The sleeve 21 is also free to turn on a shaft 17 and in arm 22.

Rigidly fastened as by rivets 24 to shaft 17 is a V-shaped head 25 to which elbow shaped arms or levers 26 are pivoted by pins 27. The longer arms of levers 26 have balls or governor weights 28 thereon while the shorter arms extend into an annular groove 29 in sleeve 21. An expansive coil 70 spring 30 surrounds sleeve 21, abutting arm 22 at one end and one of two flanges 31 at the other end, and between which flanges said groove 29 is provided. A link 32 is pivotally connected at 33 to shell 11 and at 75 34 to sleeve 21.

In use, shaft 16 constantly rotates whereby the roller 13 successively wipes the contacts 12 and thereby successively fires the spark plugs of the engine in the manner 80 well understood. The spring 30 maintains the parts, when the engine is idle in such position that cranking of the engine will not produce back-fire. When the engine is in motion, shaft 16 turns gear 20 which rotates gear 19 and shaft 17. By rotation of shaft 17, centrifugal force will throw the weights 28 outwardly from the full line to the dotted line position of Figure 1, and their position will constantly change according to 85 the speed at which such shaft 17 is driven. Weights 28 thus swing the levers 26 and by their disposition in groove 29 to slide sleeve 21 on shaft 17. This sliding movement of sleeve 21 moves link 32 and causes it to rock 95 the timer shell 11 and thereby move the contacts thereof closer or farther from the roller 13 to retard or advance the time of contact and accordingly of firing, according to the speed of the shafts 16 and 17. 100

I claim;—

In combination, a timer shell, a contact shaft coacting therewith, a shaft driven from said shaft, means mounting the second shaft against longitudinal movement, a sleeve slidable on the second shaft, a hollow arm in which said sleeve is disposed, flanges on said sleeve providing a groove between them, an expansive spring 10 rounding the sleeve and engaging one of

said flanges and said hollow arm, a head on said second shaft, elbow levers on said head extending into said groove, governor on said levers, and a link connection between said sleeve and said timer shell, said spring and link connection being on opposite sides of said hollow arm. 15

In testimony whereof I affix my signature.

JALMER ISOJOKI.
